UNITED STATES PATENT OFFICE

WILFORD H. TEETER, OF DAYTON, OHIO, ASSIGNOR TO DELCO-REMY CORPORATION, OF DAYTON, OHIO, A CORPORATION OF DELAWARE

ENGINE STARTING APPARATUS

Application filed June 14, 1928. Serial No. 235,490.

This invention relates to apparatus for starting an internal combustion engine and particularly to the type of apparatus which comprises an electric motor which operates a rotatable driving member, such as a pinion, which is moved by manual operation into operative connection with a part of the engine to be started, such as the engine flywheel gear.

One of the objects of the invention is to place the driving member substantially in complete driving connection with the engine part before operating the starting motor. Accordingly, the present invention provides manually operable means for moving the driving member or pinion along a rotatable operating device, such as a shaft, with which the driving member or pinion is operatively connected and for rotating the driving member or pinion while it is pressed against the engine part or flywheel gear in case obstruction is encountered before the driving member and engine part are operatively connected. The driving member is normally spaced from the engine part, and, while the manual means is moving the driving member toward the engine part, there is relatively little tendency to rotate the driving member. If obstruction such as gear tooth abutment is encountered before the driving member and engine part are operatively connected, continuing the manual effort to engage the driving member with the engine part will materially increase the tendency of the manually operable means to rotate the driving member while it is pressed against the engine part. This increase in tendency to rotate the driving member is proportional to the force applied to the manually operable means for connecting the driving member and engine part.

The present invention provides also for applying yielding pressure to maintain the driving member against the engine part while it is being rotated so that in case rotation of the driving member is unduly resisted by reason of the coaction of roughened engaging surfaces of the driving member and engine part, the driving member may recede from the engine part slightly in order to permit

the driving member to slip past the engine part.

A further object of the invention is to combine the features which have been described heretofore with an engine starter drive having means for automatically disconnecting the driving member from the engine part when the engine becomes self operative.

Further objects and advantages of the present invention will be apparent from the following description, reference being had to the accompanying drawings, wherein a preferred form of embodiment of the present invention is clearly shown.

In the drawings:

Fig. 1 is a fragmentary side elevation partly in longitudinal section showing engine starting apparatus embodying the present invention.

Figs. 2 and 3 are sectional views taken respectively on the lines 2-2 and 3-3 of Fig. 1.

Fig. 4 is a view similar to Fig. 1 showing the driving member or pinion abutting the engine part of flywheel gear.

Fig. 5 is a view similar to Fig. 4 showing the condition of the apparatus when the pinion has been turned to mesh with the flywheel gear but just before meshing has taken place.

Fig. 6 is a view similar to Fig. 4 showing the condition of the apparatus while crank- 80

ing the engine.

Fig. 7 is a view similar to Fig. 4 showing the condition of the apparatus after the engine becomes self-operative but before the manually operable starter control means has been released.

Referring to Figs. 1, 2, and 3, 20 designates the field frame of an electric motor which is controlled by a switch contained within a switch housing 21 and operated by a plunger 90 22 which is held normally in circuit-open-position by a spring 23. The motor operates a shaft 24 having a helically splined portion 25 which is threadedly engaged by driving member or pinion 26 movable axially along the shaft into engagement with an engine part or flywheel gear 27. The shaft 24 is supported by end bearings one of which is shown at 28 carried by a gear housing 29 connected with the field frame 20. End thrust of the pinion 100

26 while driving the gear 27 is transmitted to the shaft through a wire split-ring providing a stop-ring 30 received by a groove 31 in the shaft 24; and the end thrust of the 5 shaft is transmitted to the housing 29 through a thrust collar 32 bearing against a finished surface 33 provided by the housing.

The housing 29 includes a portion which projects through an opening 35 in that part 10 of the engine frame 36 which encloses the fly-wheel gear 27. The part of the housing 29 which is exterior of the engine frame is provided with a side opening 37 through which certain parts of the starting apparatus may 15 be passed when the apparatus is assembled. The opening 37 is closed by a cover 38 which is attached by screws 39 to plane bosses 40 and 41 provided by the housing 29, and which supports one end of a stud 42 having its other 20 end 43 supported by the housing 29 as shown in Fig. 2. The stud 42 supports an operating lever 44 having a hub 45 journalled upon the stud. The upper arm of the lever 44 is located so as to actuate the switch plunger 25 and is attached to a pedal rod 46 which passes through a cup member 47 extending through an opening 48 in the floorboard 49 of the automobile. A spring 50 located between the bottom of the cup member 47 and the head 51 30 of the pedal rod 46 serves normally to maintain the lever 44 in the position shown in Fig. 1.

The shaft 24 supports an engagement-effecting member 60 which slides axially along 35 the shaft in order to move the pinion 26 into engagement with the gear 27, and which is manually rotatable for the purpose of rotating the pinion 26 into meshing relation with respect to the engine gear 27. Rotary motion 40 is transmitted from the member 60 to the pinion 26 by clutch teeth 61 provided by member 60 and engageable with clutch teeth 62 provided by a disk 63 attached to the pinion 26. In order that downward movement 45 of the pedal 51 may cause the member 60 to move axially and to rotate when necessary to effect registration of the pinion with the gear, the lever 44 is connected with the member 60 in a manner such that while the pinion 26 50 is being moved by the member 60 into contact with the gear 27 there is relatively little tendency to rotate the member 60, but the tendency to rotate the member 60 will increase with increasing pressure upon the pedal 51 55 while the pinion 26 is pressed against the gear 27. This effect is accomplished by connecting the lever 44 to the member 60 by a collapsible link comprising telescopically engageable tubular like members 64 and 65 60 which are normally maintained in extended relation by a spring 66 contained within these portions. A screw pin 67 attached to the member 64 and passing into a slot 68 in the member 65 limits the extent to which the members 64 and 65 can be separated. The

link member 64 carries a stud 69 received by a hole in the lower end of the lever 44. The link member 65 is connected with the engagement-effecting member 60 by a stud 70 which is shaped so as to permit rotation of the member 60 while the link moves bodily along the shaft 24, and so as to retain the link member 65 in cooperative relation with the member 60, as shown in Fig. 2.

Normally the members 64 and 65 of the collapsible link are extended and the link is normally located at a relatively small angle relative to the axis 24. Therefore, when the pedal 51 is pressed to start the engine, the lever 44 and the collapsible link transmit motion from the pedal in such a manner that the tendency to rotate the member 60 is relatively small in comparison with the tendency to move it axially along the shaft 24. The pressure upon the pedal 51 first causes the link to move from the position shown in Fig. 1 to that shown in Fig. 4 in order to cause a finger member 71 provided by the link member 65 to engage the disk 63 and to move the pinion 26 into contact with the gear 27. If gear tooth abutment occurs, continued pressure upon the pedal 51 will cause the link to collapse and shorten the distance between the axes of the studs 69 and 70 as will be apparent from Figs. 4 and 5. While the link is thus shortening and changing its angular relation to the shaft 24 the finger 71 will be so moved as to permit engagement of the clutch teeth 61 and 62 so as to transmit rotary motion from the member 60 to the pinion 26. The shortening of the link changes the angular relation between the axis of the member 60 and a center line joining the axes of the studs 69 and 70. Therefore, as the lever 44 is moved from the position shown in Fig. 4 to that shown in Fig. 5 the component of the force transmitted by the link to the member 60 which tends to produce rotation in the member 60 materially increases so that the pinion 26 will be rotated during movement of the lever 44 from the position shown in Fig. 4 to that shown in Fig. 5. Sufficient rotation is imparted manually to the pinion 26 to cause it to move from an abutting relation to a gear meshing relation with respect to the gear 27. At the instant the gear meshing relation is accomplished the spring 66 will be released in order to assist the pedal 51 in moving the pinion 26 into mesh with the gear 27.

Before the motor switch will have been closed by the lever 44 coacting with the switch plunger 22, the pinion 26 will have been moved a substantial distance into mesh with the gear 27. The closing of the switch will cause the motor to turn the shaft 25 in the direction of the arrow 75 and will move the pinion endwise against the stop ring 30 so that the pinion will be fully meshed with the gear as shown in Fig. 6. It will be noted that the clutch teeth 62 are free of the clutch teeth

61 during the engine cranking operation and that the finger 71 provided by the collapsible link is located in advance of the teeth 61. When the engine becomes self operative the 5 pinion 26 will be automatically demeshed from the engine gear 27 due to the reversal of end thrust produced by the splines upon the pinion when the engine rotates the pinion faster than it can be rotated by the starting 10 motor. As the pinion is whirled rapidly out of mesh with the engine gear the disk 63 will engage the finger 71 to move it forcibly from the position shown in Fig. 6 to that shown in Fig. 7. In order to maintain the clutch 15 teeth 61 out of engagement with the clutch teeth 62 while the motor shaft is still rotating, the collapsible link is maintained automatically in the position shown in Fig. 7 by a compression spring 80 which has been located 20 as shown in Fig. 7 so that it exerts a force tending to rotate the link in a counter clockwise direction about its pivot stud 69. The spring 80 surrounds an arm 81 pivotally connected with the link member 64 by a pin 82, 25 and the upper end of the arm 81 is slidably connected with a bushing 83 carried by the hub 45 of the lever 44. The upper end of the spring 80 bears against a washer 84 bearing against the lower end of the bushing 83, and 30 the lower end of the spring bears against the washer 85 bearing against a shoulder 86 provided by the link 81. Normally the line of 35 action of the spring 80 is located to the right of the axis of the pivot stud 69 as shown in Figs. 1, 4, 5, and 6; but when the pinion is automatically demeshed from the gear the spring 80 is located so that its line of action is located to the left of the stud 69 as shown in Fig. 7. When the pedal 51 is released 40 the spring 50 will return the lever 44 to normal position and the spring 80 will be reconditioned for biasing the link in a clockwise direction and for tending to resist rotation of the engagement-effecting member 60.

45 The pinion 26 is hindered from accidentally moving into mesh with the gear 27 by reason of the fact that the pinion normally is supported by a splined portion 25a of lesser outside diameter than the splined portion 25b which receives the pinion while it is cranking the engine. The portions 25a and 25b are separated by conical, interrupted shoulder portions 25c which provide sufficient obstruction to hinder movement of the pinion accidentally into contact with the engine gear while the engine is running.

50 It will be noted that motion is transmitted through a yielding spring 66 to the engagement-effecting member 60 in order that the pinion will be yieldingly pressed against the engine gear while attempting to rotate it into meshing registration therewith. This feature is important especially in case of a condition where the teeth of the pinion interlock 55 with the abutting teeth of the gear so that it

becomes difficult to rotate the pinion. This interlocking condition may occur occasionally after the end surfaces of the pinion and gear teeth have become slightly roughened in use. Since the pedal pressure is transmitted 70 yieldingly to the pinion the pinion is free to move a slight amount to the left relative to the gear in order that the interlocking condition may be relieved and that the pinion may continue to rotate. 75

75 While the form of embodiment of the present invention as herein disclosed, constitutes a preferred form, it is to be understood that other forms might be adopted, all coming within the scope of the claims which follow. 80

What is claimed is as follows:

1. An engine starter drive comprising a rotatable driving member axially movable into engagement with a rotatable part connected with an engine to be started; and manually operable means for moving the driving member axially and for turning it when necessary to effect its engagement with the engine part, said means including a device for engaging said driving member to axially move and turn the same, a part movable longitudinally with respect to the axis of the driving member, a spring for transmitting motion from the part to the device in a direction oblique to and eccentric to the axis of the driving member, and manually operable means for moving said part. 90

2. An engine starter drive comprising a rotatable driving member axially movable into engagement with a rotatable part connected with an engine to be started; an axially and rotatably movable device for effecting engagement of the driving member with the engine part; means for transmitting rotary movement from the device to the driving 100 member, and manually operable means for exerting force upon the engagement-effecting device in a direction oblique and eccentric to its line of axial movement in order to tend to axially move and to rotate the engagement-effecting device, said means including a part movable longitudinally with respect to the axis of the driving member, a spring for transmitting motion from the part to the device in a direction oblique to and eccentric to 105 the axis of the device, and manually operable means for moving said part. 110

3. An engine starter drive comprising a rotatable driving member axially movable into engagement with a rotatable part connected with an engine to be started; and manually operable means for moving the driving member axially and for turning it when necessary to effect its engagement with the engine part, said means including a device for engaging said driving member to axially move and turn the same, an actuator movable along the axis of the driving member, and a yielding link connecting the actuator and device and extending oblique to and eccentric 120 to the axis of the device. 125

to the axis of the driving member, an actuator and a link including a spring force transmitting member variable in length according to the amount of force transmitted by it for applying a force from the actuator upon the driving member oblique and eccentric to its axis, the variation in length of the link causing the angle between the direction of force application and the axis of the driving member to increase in response to continuing the movement of the actuator after the driving member meets with obstruction by the engine part before connecting therewith.

4. An engine starter drive according to claim 3 in which the variable link comprises two telescopically-engageable, tubular members, and in which the compression spring is enclosed by the tubular members and tends to maintain said members extended.

5. An engine starter drive comprising a rotatable driving member axially movable into engagement with a rotatable part connected with an engine to be started; and manually operable means for moving the driving member axially and for turning it when necessary to effect its engagement with the engine part, said means including an actuator, an engagement-effecting member movable axially and rotatively for connecting said driving member with the engine part, and a link connected with the actuator and engagement-effecting member and movable along the axis thereof and eccentric and oblique thereto, said link including a spring force transmitting member varying in length according to the force transmitted by it in order to cause an increase in the angle between the direction of force application through the link and the axis of the engagement-effecting member in response to continuing the movement of the actuator after the driving member meets with obstruction by the engine part before connecting therewith.

6. An engine starter drive comprising a rotatable driving member axially movable into engagement with a rotatable part connected with an engine to be started; and manually operable means for moving the driving member axially and for turning it when necessary to effect its engagement with the engine part, said means including an actuator, an engagement-effecting member movable axially and rotatively and coaxial with the driving member, axially-engageable, normally-disengaged clutch members provided respectively by the engagement-effecting member and driving member, and a link connected with the actuator and engagement-effecting member and movable along the axis thereof and eccentric and oblique thereto, said link including a spring force transmitting member varying in length according to the force transmitted by it in order to cause an increase in the angle between the direction of force application through the link

and the axis of the engagement-effecting member in response to continuing the movement of the actuator after the driving member meets with obstruction by the engine part before connecting therewith.

7. An engine starter drive according to claim 6 in which the actuator operates a pivot pin along the axis of the engagement-effecting member and in which the variable link connects the pin with the engagement-effecting member at a point eccentric to its axis.

8. An engine starter drive according to claim 6 in which the actuator operates a pivot pin along the axis of the engagement-effecting member and in which the variable link comprises two tubular telescopically, engageable members and a compression spring enclosed thereby, one member being connected with the pin and the other with the engagement-effecting member at a point eccentric to its axis.

9. An engine starter drive comprising a drive shaft, a pinion connected with the shaft and movable axially therealong into engagement with a gear connected with the engine to be started, and manually operable means for moving the pinion axially and for turning it when necessary to mesh it with the engine gear, said means including an actuator movable along the axis of the pinion but spaced therefrom, and mechanism for transmitting motion to the pinion oblique and eccentric to the axis of the pinion whereby to provide force-components tending, respectively, axially and rotatively, to move the pinion, said mechanism including a device for engaging the pinion to axially move and turn the same, and a yielding motion transmitting member connecting the actuator and device and extending oblique to and eccentric to the axis of the pinion.

10. An engine starter drive comprising a drive shaft, a pinion connected with the shaft and movable axially therealong into engagement with a gear connected with the engine to be started, a rotatable clutch member movable along the shaft and axially engageable with a companion clutch member provided by the pinion; and manually operable means for moving the clutch member axially in order to move the pinion toward the gear and for rotating the clutch in order to rotate the pinion to effect registration, said means including an actuator movable along the axis of the clutch but spaced therefrom and mechanism for transmitting motion oblique and eccentric to the axis of the clutch member whereby to provide force-components tending, respectively, axially and rotatively, to move the pinion, said mechanism including a spring motion transmitting member whereby the rotatively-movement force-component will increase relative to the other component

if movement of the actuator is continued after the pinion is obstructed by the gear.

11. An engine starter drive comprising a drive shaft, a pinion connected with the shaft and movable axially therealong into engagement with a gear connected with the engine to be started; a rotatable clutch member movable along the shaft and axially engageable with a companion clutch member provided by the pinion; and manually operable means for moving the clutch member axially in order to move the pinion toward the gear and for rotating the clutch in order to rotate the pinion to effect registration, said means including a pivot pin movable along the shaft and a link extending oblique and eccentric to the clutch member and connecting the pivot pin with a part of the clutch eccentric thereto, said link including a spring force transmitting member varying in length according to the force transmitted through it whereby the angle between the link and axis of the clutch will increase if movement of the pivot pin continues after the pinion is obstructed by the gear.

12. An engine starter drive according to claim 11 in which the variable link comprises a compression spring enclosed by two tubular, telescopically-engageable members, one connected with the pin and the other with the clutch.

13. An engine starter drive comprising a rotatable driving member axially movable into engagement with a rotatable part connected with an engine to be started; and manually operable means including a spring motion transmitting member for applying a force yieldingly and oblique and eccentric to the axis of the driving member in order to move it axially and to rotate it when necessary to effect its driving engagement with the engine part.

14. Engine starting apparatus comprising a motor, means for connecting the motor with a rotatable part of the engine to be started and including a driving member and provisions whereby the driving member will be automatically demeshed from the engine part when the engine starts; and manually operable means including a spring motion transmitting member for moving the driving member against the engine part with yielding pressure and for turning the driving member in case it collides with the engine part before being connected therewith.

15. Engine starting apparatus comprising a motor, means for connecting the motor with a rotatable part of the engine to be started and including a driving member and provisions whereby the driving member will be automatically demeshed from the engine part when the engine starts; and manually operable means including a spring motion transmitting member for applying a force yieldingly and oblique and eccentric to the axis

of the driving member in order to move it axially and to rotate it when necessary to effect its driving engagement with the engine part.

In testimony whereof I hereto affix my signature.
